Primary Examiner — Leanne Was-Englehart*Assistant Examiner* — Sherry L Jones(74) Attorney, Agent, or Firm — Jen-Feng Lee, Esq.(57) CLAIM

The ornamental design for a pet car seat cover as shown and described.

DESCRIPTION

FIG. 1 shows a perspective view of the pet car seat cover showing my new design, depicted in a position of use;
 FIG. 2 shows a front view thereof;
 FIG. 3 shows a rear view thereof;
 FIG. 4 shows a right side view thereof, with the opposite side being a mirror image thereof;
 FIG. 5 shows a top view thereof;
 FIG. 6 shows a top view thereof, shown in a flat position; and,
 FIG. 7 shows a bottom view thereof, shown in a flat position. The broken lines depict environmental subject matter, are for illustration only, and form no part of the claimed design.
